COMBINED IRRITANT GAS PROJECTOR AND FLASHLIGHT

James N. Waldorf, 16230 Benwood,
Covina, Calif. 91722

Filed Mar. 17, 1975, Ser. No. 558,823

Term of patent 14 years

Int. Cl. D22—01; D26—02

U.S. Cl. D48—24 A

FIG. 1 is a perspective view of a combined irritant gas projector and flashlight, showing my new design;

FIG. 2 is an elevational view on a reduced scale;

FIG. 3 is an end view thereof; and

FIG. 4 is a view of the end opposite from that shown in FIG. 3.

The combined irritant gas projector and flashlight is shaded with cross-hatching to indicate contrast. The cross-hatching is partially shown for convenience of illustration, it being understood that the cross-hatching is uniformly continuous over the areas on which it appears.

I claim:

The ornamental design for a combined irritant gas projector and flashlight, as shown and described.
